UNITED STATES PATENT OFFICE.

ALBERT BORCHARDT, OF WEEHAWKEN, NEW JERSEY.

MACHINE FOR SEWING BUTTONS TO FABRICS.

SPECIFICATION forming part of Letters Patent No. 256,278, dated April 11, 1882.

Application filed December 2, 1881. (Model.)

To all whom it may concern:

Be it known that I, ALBERT BORCHARDT, of Weehawken, New Jersey, have invented certain Improvements in Mechanism for Sewing on Buttons, of which the following is a specification.

My improvement is applicable to several varieties of button-hole machines and under-feed sewing-machines in which the cloth-plate is laterally reciprocated; and my invention consists of a button-holder in which the button is held by its edge, and by which it is pressed directly upon the surface of the fabric to which it is to be sewed, whereby the button itself is made the presser-foot of the machine. The button-holder is carried by suitable mechanism, which may be connected with the movable cloth-plate upon which the fabric rests. By means of such mechanism the button-holder is elevated to receive a button, and depressed to press the button against the fabric.

The accompanying drawings, illustrating my button-holder and the mechanism with which it is immediately connected, which may be affixed to or connected with the bed of the sewing-machine, are as follows:

Figure 1 is a side elevation, showing the button-holder depressed in the position which it occupies when pressing the button down upon the fabric to which the button is to be sewed, and also exhibiting in dotted lines the elevated position which the button-holder is made to assume for convenience in inserting the button in it. Fig. 2 is a top view. Fig. 3 is a transverse section through the broken line $x-x$ on Fig. 2; and Fig. 4 is a view of the under side of the plate to which the button-holder is attached, showing the button and a portion of the under side of the button-holder, and also showing the spring-jaw for clamping the button in its seat, a portion of the plate being represented as broken out for the purpose of more clearly exhibiting the spring-jaw.

The drawings represent a plate, A, which is attached to that part of the sewing-machine to which a reciprocating motion is given in a plane perpendicular to the path of the needle.

The button-holder B is carried in the end of the forked hinged plate C, to which it is attached by the screws C'. The holes in the ends of the forked plate C are somewhat larger

than the shanks of the screws C', in order to give the button-holder a slight range of oscillation upon a horizontal axis, and thus enable it to press the button D squarely down upon the fabric which is to be sewed.

The hinged plate C is perforated to admit the post A' carrying the presser-cam A², by the action of which the hinged plate C is pressed downward against the outward thrust of the expanding spiral spring A³. The hinged plate C is provided with two rearwardly-projecting arms, C², the ends of which are loosely inserted respectively in the standards A⁴, affixed to the plate A. The central portion of the plate A is slotted to admit the button-holder and to allow the under part of the button to be projected completely through the plate A.

The button D is held in the button-holder by means of the curved rail B' and the spring-jaw B², against which the edge of the button bears, and by which slightly more than one-half the periphery of the button is embraced. When the button is to be inserted in the button-holder the hinged plate C is allowed to swing upward into the position shown by dotted lines in Fig. 1, and the button is then slid along the under side of the button-holder until it brings up against the curved rail B'. The spring-jaw B² yields outwardly as the button is pushed along the under surface of the holder, and when the button is seated against the rail B' is made to bear against the edge of the button by the spring B³. The oscillating plate C is then swung downward by means of the presser-cam A², and the under surface of the button is thus made to bear directly upon the surface of the fabric to which the button is to be sewed, the button itself thus acting as the presser-foot of the machine. The position of the plate A fixes the button in proper position with relation to the needle, and by the reciprocating feed of the machine the stitches are formed alternately on either side of the bar D' of the button, the thread being carried over the bar alternately in opposite directions as the stitches are successively made.

The button represented in the drawings is of that class in which there is a central eyelet provided with a transverse bar, and a lateral reciprocating motion of the bed upon which the fabric rests, or a lateral reciprocating mo-

tion of the needle-bar, if the bed be stationary, is all that is required to enable such buttons to be sewed on by the machine. If, however, it be desired to use buttons having four holes 5 for the admission of the threads by which they are sewed on, the feed-motion of the bed upon which the fabric rests will of course be so modified as to bring the four holes successively into alignment with the needle. As these feed-motions do not form a part of my present invention, and are common in button-hole machines, no special description of the mechanism by which they are effected is required.

It will of course be seen that my invention 15 is applicable to all those classes of buttons which are sewed on by means of threads carried transversely through the body of the button, or through holes therein.

I claim as my invention—

20 1. The button-holder B, provided with means for holding a button by its edge, so that it may be lowered upon the fabric, in combination

with means, substantially as described, for pressing the button directly upon the surface of the fabric to which it is to be sewed, as set 25 forth.

2. The button-holder B, provided upon its under surface with a fixed bearing for a portion of the edge of the button, and with a movable jaw bearing with elastic pressure upon 30 the edge of the button and serving to hold the button in place, in combination with means for pressing the button directly upon the surface of the fabric to which it is to be sewed, substantially as described.

3. The slotted plate A, in combination with the hinged plate C and the button-holder B, adapted to carry a button, substantially as and for the purpose set forth.

ALBERT BORCHARDT.
